UNITED STATES PATENT OFFICE.

WILLIAM T. HAEN, OF MINNEAPOLIS, MINNESOTA.

BELT BUCKLE.

Application filed September 24, 1923. Serial No. 664,566.

To all whom it may concern:

Be it known that I, WILLIAM T. HAEN, a citizen of the United States, residing at Minneapolis, in the county of Hennepin and State of Minnesota, have invented a new and useful Belt Buckle, of which the following is a specification.

My invention relates to improvements in belt buckles.

10 An object of the invention is to provide a belt buckle that is pleasing in appearance and comfortable to the wearer and one that is not only simple and durable in construction, but effective in use and readily manipulated.

15 With the foregoing and other objects in view, which will appear in the following description, the invention resides in the novel combination and arrangement of parts 20 and in the details of construction herein-after described and claimed.

In the drawings, Figs. 1 and 2 are perspective views illustrating, respectively, the front and back of a buckle embodying my 25 invention; Figs. 3 and 4 are enlarged, central, longitudinal sectional views taken as on the line $x-x$ of Fig. 2 and Fig. 5 is a perspective view in detail of the belt clamping member.

30 Referring to the drawing, it will be observed that my invention includes a frame A and a belt clamping member B slideable therein. The frame A is a channel-like structure comprising a web 10 and back 35 turned flanges 11. Posts 12, 13 secured at their ends to said flanges 11 and spaced apart from each other and from the web 10 serve, among other things, as keepers for the member B. One end c^2 of a belt or strap 40 C employed in connection with my buckle is attached to the frame A by means of a releasable jaw D of conventional form, the other end c^2 of said belt being threaded through the buckle between the web 10 of 45 the frame A and the belt clamping member B, as shown in Figs. 3 and 4.

The clamping member B is struck from a thin metallic strip. One end of this strip is turned back to form a rearwardly inclined cam portion 14. The other end of said strip is bent to form a second rearwardly inclined cam portion 15 and is looped back from said cam portion 15 to form a rearwardly projecting body engaging portion 16 and opposed stops 17 and 18.

The intermediate part of the strip constitutes a gripper plate 19 and said plate is punched as at 20 to form a plurality of belt engaging teeth 21. The cam portions 14, 15, which are substantially parallel, ride against the posts 12, 13 and, coacting with these abutments, cause the plate 19 to grip the belt (Fig. 3) or release the same (Fig. 4), according to the longitudinal relation of said member B with respect to the frame A. 60

The post 13 reaches through the loop in the end of the clamping member B and acting as an abutment for the stops 17, 19, limits the reverse sliding movements of said member B. 70

With the belt around a wearer's body, the end c^2 thereof is threaded between the member B and the web 10 of the frame A. In thus applying said end of the belt, the stop 18 is employed as a finger piece for retracting the member B and thereby providing for the ready insertion of the belt into the buckle. In tightening the belt, the portion 16 of the member B is brought against the wearer's body and upon releasing said belt, 80 the pressure of the body against said portion 16 brings the plate 19 against the belt. Under limited slippage of said belt, the frictional contact of the plate 19 therewith and the forward pressure on the body engaging portion 16 causes the cam portions 14 and 15 to ride in the direction of their high sides against the posts 12, 13. This co-action of said cam portions and posts 90 clamps the plate 19 from end to end against the belt and firmly grips said belt in the frame A. The cam portions 14, 15 yield slightly in wedging against the posts, thus rendering the member B self-compensating to variations in belts. Traversing the high 95 sides of the cam portions 14, 15 are recesses or scores 14', 15' which are engaged by the posts 12, 13, when the member B is shifted to belt clamping position (Fig. 3). The engagement of said posts with the scores in said cam portions yieldingly latches said member B against retraction and this, together with the pressure of a wearer's body against the body engaging portion 16, firmly holds the member B in belt gripping position. 100

In releasing the grip of the buckle upon the end c^2 of the belt, said end of the belt is drawn into the buckle far enough to retract the member B (Fig. 4) and remove the 110

pressure of the plate 19 from the belt. The stop 18 may be employed as a finger piece to aid in thus retracting said member and to hold the same retracted while the belt is drawn out of the buckle.

Among the several distinctive advantages resident in my improvement, particular attention is invited to the following: The plate 19 affords a belt gripping surface of substantial area. The resiliency of this plate and of the cam portions 14, 15 renders the member B self-compensating to variations in belts, yet affords a positive gripping action. The post engaging scores 14', 15' in the cam portions 14, 15 yieldingly latch the clamping member B. The body engaging portion 16 on the member B supplements the frictional locking action of the belt on said member B and the latching action of the post engaging scores 14', 15' in the cam portions 14, 15. Said body engaging portion 16 serves as a finger piece to aid in bringing the member B into belt clamping position and the stop 18 serves as a finger piece in retracting said member from said position and thus holding the same while a belt is withdrawn from the buckle.

Changes in the specific form of my invention, as herein disclosed, may be made within the scope of what is claimed without departing from the spirit of my invention.

Having described my invention, what I claim as new and desire to protect by Letters Patent is:

1. In a belt buckle, a channel-like frame and a member slidable therein for clamping a strap against the web of said frame, said member comprising a resilient metallic strip, one end being turned back to form a yielding cam portion, the other end of said strip being bent to form a second yielding cam portion, and looped back from said second cam portion to form a rearwardly projecting body engaging portion and opposed stops, two posts secured at their ends to the flanges of the frame and comprising keepers for said member, one of said posts being arranged within the looped end of said clamping member and providing an abutment for co-action with the cam portion and stops thereon, the other post being arranged for co-action with the cam

portion at the opposite end of said member, 55 said cam portions being scored to yieldingly catch said posts.

2. In a belt buckle, a channel-like frame and a member slidable therein for clamping a strap against the web of said frame, said member comprising a metallic strip, one end being turned back to form a cam portion, the other end of said strip being bent to form a second cam portion, and looped back from said second cam portion to form 60 a body engaging portion and opposed stops, two posts secured at their ends to the flanges of the frame and comprising keepers for said member, one of said posts being arranged within the looped end of said clamping member and providing an abutment for co-action with the cam portion and stops thereon, the other post being arranged for co-action with the cam portion at the opposite end of said member. 70

3. In a belt buckle, a channel-like frame and a member slidable therein for clamping a strap against the web of said frame, said member comprising a metallic strip, one end being turned back to form a cam 75 portion, the other end of said strip being bent to form a second cam portion, and looped back from said second cam portion to form a rearwardly projecting body engaging portion, abutments on the flanges of 80 the frame comprising keepers for said member, said abutments being arranged to coact with said cam portions.

4. In a buckle, a channel-like frame and a member slidable therein for clamping a 85 strap against the web of said frame, abutments carried by the flanges of the frame, said member comprising a belt engaging plate and yielding cam portions thereon coacting with said abutments. 90

5. In a belt buckle, a frame, a clamping member slidable therein and comprising a belt gripping plate, a cam portion and a portion for engaging the body of a wearer, an abutment carried by the frame for co-action with said cam portion, said body engaging portion being adapted to forcibly bring said plate into contact with the belt and thereby promote positiveness of action between said cam portion and abutment. 95

In testimony whereof, I have signed my name to this specification.

WILLIAM T. HAEN.
